UNITED STATES PATENT OFFICE.

ARTHUR W. CASH, OF DECATUR, ILLINOIS, ASSIGNOR, BY DIRECT AND MESNE ASSIGNMENTS, TO THE TYPOGRAPH COMPANY, OF HARTFORD, CONNECTICUT.

TYPE-WRITING MACHINE.

SPECIFICATION forming part of Letters Patent No. 425,931, dated April 15, 1890.

Application filed May 9, 1884. Serial No. 130,845. (No model.)

To all whom it may concern:

Be it known that I, ARTHUR W. CASH, a citizen of the United States, residing at Decatur, in the county of Macon and State of Illinois, have invented certain new and useful Improvements in Type-Writing Machines, of which I do declare the following to be a full, clear, and exact description, reference being had to the accompanying drawings, forming part of this specification.

My present invention has for its object to provide an improved construction of type-writing machine wherein the paper upon which the printing is done shall be so held as to be constantly in view of the operator during the printing operation, that he may clearly see the character of his work as it progresses and can readily and immediately correct any errors that may occur.

20 A further object of my invention is to provide an improved clamp for holding the paper to be printed upon its carriage and to furnish an improved construction of escapement for controlling the movement of this carriage in forming the space between each letter and word.

25 My invention has also for its object to decrease the usual number of keys on the keyboard by providing a portion or (if desired) all the type-levers with several types having different letters or characters thereon, and with improved means whereby these types may be made to strike at a common point on the paper-carriage.

30 My invention has for its further object to provide improved means whereby the ink-ribbon commonly employed in type-writers may be dispensed with and the types may be thrown after each impression against an ink-pad to properly supply their face with ink.

35 My invention has for its object also to improve the construction of type-writing machines in various details, as will hereinafter more fully appear.

40 These several objects of my invention I have accomplished by the mechanism set out in the following description, illustrated in the accompanying drawings, and particularly de-

fined in the claims at the end of this specification.

Figure 1 is a plan view of a type-writer embodying my invention, parts being broken away for the purpose of better illustration. Fig. 2 is a detail view, partially in horizontal section, of my improved escapement mechanism. Fig. 3 is a view in front elevation. Fig. 4 is a view in transverse section on line *xx* of Fig. 1. Fig. 5 is a view in longitudinal vertical section on line *yy* of Fig. 1. Fig. 6 is a view in vertical longitudinal section through the front portion of the machine, the main key-lever being shown in depressed position. Fig. 7 is a detail view in vertical longitudinal section of the end portions of the paper-carriage, illustrating the paper-clamp. Fig. 8 is a fractional view in end elevation of the paper-carriage. Figs. 9, 10, and 11 are views respectively in side and front elevation and plan of the improved type-lever for carrying two types and its connected parts. Figs. 12 and 13 are views respectively in rear and side elevation of my improved form of type-lever for carrying a single type and the parts connected thereto. Fig. 14 is a view in side elevation of the front portion of the machine, parts being broken away to show the ratchet-wheel, ratchet, and key-lever for making the spaces between the lines.

Like letters and figures of reference denote corresponding parts in the several views of the drawings.

A designates the frame of the type-writer, the front portion of which is of less depth than the main body, and is provided with a perforated plate *A'*, that constitutes the keyboard of the machine. The top plate *A²* of the body of the machine is furnished with the rails *a*, upon which travels the movable frame or table *B*, that supports the paper-carriage *C*, having suitable grooves to receive the rails *b* of this table. To the lower portion of this table *B* is attached the rack-bar *b'*, that moves within the groove *a²* of the top plate *A²* and meshes with the driving-pinion *B'*, that is loosely fitted on the inner end of the shaft *B²*, but derives motion from this shaft by reason

of its frictional contact with the plate b^3 , keyed to the shaft, against which plate it is pressed by the coiled spring B^3 . The inner end of the shaft B^2 is sustained by the journal-bracket d^3 , while its outer end passes through the side of the main frame and carries the ratchet-wheel B^4 , that will receive its rotation from the pawl b^3 on the end of the line-space lever B^5 , pivoted, as at b^4 , to the side 5 of the main frame, pressed normally upward by the spring b^5 , and provided with the finger-key b^6 . Over the top of the plate A^2 throughout its length extends what I designate the "main driving-shaft" D , having its front and 10 rear ends held, respectively, in the journal-brackets d and d' and carrying upon its forward portion the coiled spring D' , resting within a groove of the top plate A^2 and having one end rigidly connected to the shaft 15 and the opposite end fixed to the top plate. Upon the driving-shaft D is placed the driving-pinion E , having a spline or feather adapted to fit within the long groove d^2 , that extends from about the center of the shaft to 20 its rear end, so that as the driving-pinion is moved along the shaft it will still derive its movement therefrom. To the side of the pinion E is connected the grooved hub e , around which fits the plate e' , that is rigidly secured 25 to the rear side of the frame or table B , so that any movement of the table shall cause a like movement of the driving-pinion along the shaft. A rack-bar c on the under side of 30 the paper-carriage C is in gear with the driving-pinion, and it is from this rack-bar and pinion that lateral movement at right angles to the line of travel of the frame or table B is imparted to the carriage, as will presently appear. A long broad slot a^2 , having inclined 35 or curved sides, is formed in the top plate A^2 , as seen in Fig. 1, to permit the free movement of the driving-pinion E . On the under side of the paper-carriage C is fixed the rail or rib c^2 , having a groove throughout its length to receive the bent end of the bracket c^3 , attached 40 to the rear part of the frame or table B and serving to hold the paper-carriage securely 45 upon the table.

Upon the front end of the driving-shaft D is loosely held the escapement-wheel F , with the teeth of which engage the forwardly-bent end g of the escapement-pawl G and the free end of the spring-stop G' , that is fixed to the top of this pawl. The pawl G is sustained 50 by the pivot-pin g' , and by means of the link g^3 , that connects with the cross-bar G^2 , passing beneath each of the main key-levers and held against the same by the spring g^3 , is moved each time either of the keys is depressed, as will hereinafter more fully appear. In the escapement-wheel F are formed the holes f , adapted to receive the pin h , that projects from the lever H through the crank-arm I , keyed on the end of the drive-shaft D . 55 Lugs i are formed on this crank-arm, and through these and corresponding lugs on the lever H passes the pin h' , by which the lever

is pivotally held on the crank-arm. A pin i' on the end of the crank-arm enters the perforated knob I' of the lever H , and a spring i^2 70 serves to keep the pin h pressed normally into the pin-holes of the escapement-wheel, so that the escapement-wheel will be turned by the shaft until the pin h is withdrawn.

The sheet of paper upon which the impression is to be made is held in place upon the paper-carriage by means of the angular clamp-strip K , having ears k , pivoted to the sides of the carriage at k' , and having in its front portion the long slot k^2 , in which works 80 the crank-shaped end of the clamp-rod K' , that extends through the paper-carriage and is furnished at its front end with the turning-knob k^3 . A coil-spring k^4 on the rod K' serves to hold the clamp-strip against the 85 paper.

The operation of the mechanism thus far described is as follows: The sheet of paper upon which the impressions are to be made is placed upon the paper-carriage with its top edge beneath the clamp-strip K , and by the action of the spring k^4 , tending to depress the clamp-strip, is there securely held. The frame or table B , that sustains the paper-carriage C , is then at the front of the machine, and the paper-carriage is at the right-hand side, as seen in Fig. 1, the coil-spring D' being wound and under tension. As the finger-keys are now operated to cause the types to print, the cross-bar G^2 is depressed, and it in turn trips the escapement-pawl G and spring-stop G' , so as to allow the escapement-wheel to turn the distance of one tooth as each finger-key is released and its type-lever rises. By this turning of the escapement-wheel the driving-shaft D causes the pinion E to move the rack-bar c and the paper-carriage a sufficient distance for the printing of the next succeeding letter. In this manner the space is made between letters and words until the end of the line is reached, when by pressing upon the knob I' the lever H will be depressed until the pin h is withdrawn from the escapement-wheel, and by now turning the crank-arm H the pinion E will be forced to move the paper-carriage back to its first position and the coiled spring will be wound to move the escapement-wheel when the pin h is again placed therein and the escapement-pawl is operated. In order to move the paper-carriage forward a space sufficient for the next succeeding line, the line-space lever B^5 at the side of the machine will be depressed, thereby causing the pawl b^3 to turn the ratchet-wheel B^4 and impart a corresponding movement to the pinion B' and rack-bar b' . As the pinion B' is held against the plate b^2 by frictional contact, (see Fig. 4,) it will be seen that when the printing of the sheet is finished the carriage-sustaining table can be drawn again to 105 the front of the machine by using sufficient force to overcome the frictional contact of this pinion.

I shall now describe my improved construc-

tion of type-levers and mechanism for operating the same, referring first to that form wherein two types are sustained upon a single lever in such manner that either may be caused to strike at the common printing-point. A description of a single one of these levers and its connected parts will suffice for all.

Through one of the slots a^4 of the key-board plate A' projects the stem l of the finger-key L, the lower end of this stem passing through a perforation in the plate or strip L' , that extends across the machine, a like strip being provided beneath each row of keys. About the center of the key-stem is fixed a stop l' , that rests within a seat l^2 in the end of each main key-lever M, being held therein in such manner as to permit a slight rocking movement of the stem. The key-lever M is pivoted, as at m , to the depending bracket m' , (see Fig. 5,) and to its rear portion is connected the spring m^2 , that bears against the under side of the top plate A^2 and serves to keep the keys normally in elevated position. To the lever M is pivotally attached, as at m^3 , the swinging angle-plate M' , through the bottom of which projects the bent end m^4 of the catch-rod M^2 , the rear end of which passes through and is sustained by the clip m^5 on the end of the lever. To the top of the swinging plate M' is attached the rear end of the pitman N, through an eye in the front end of which passes the stem l of the finger-key. A spring n , also connected to the swinging plate, tends to hold this plate in the vertical position shown in Fig. 5. When the swinging plate M' is in its vertical position, the end of the catch-rod M^2 projects just through the elbow-lever O, pivoted within a slot a^5 of the main frame, as at o , so that when a key is forced vertically downward this lever alone is operated. If, however, the key be simultaneously depressed and drawn backward, as seen in Fig. 6, the pitman N will cause the swinging plate M' to force the catch-rod out a sufficient distance to lift the elbow-lever P, also pivoted within the slot a^5 of the main frame. The upper end of the elbow-lever O is connected by the link o' to the bent lower end of the main type-lever R, that is pivoted at r to the bracket-plate r' , screwed to the segment-plate A^5 , sustained by the casting A^6 . In the upper end of the type-lever is journaled the pin s , that has fixed thereto at one side of the type-lever the type-carrying head S, and has keyed thereto at the opposite side of the lever the pinion S' , that meshes with the rack-bar t of the turning-lever T, the rack-bar and pinion being held securely together by means of the guide-clip t' , connected to the end of the type-lever and clasping the turning-lever, as seen in Fig. 10. The type-carrying head S is provided with two prongs 1 and 2, each of which is drilled out to receive the shank of a type s' , that bears upon its face any desired letter or character. The lower end of the turning-lever T is joined

to link T' , pivoted to the bracket-plate r' at r^2 , at which point is attached the link T^2 , that connects the turning-lever with its elbow-lever P. The type-levers will be placed around the curved front portion of the segmental plate A^5 and will be of proper length to deliver each type at the time of making its impression at a common printing-center above the paper-carriage.

Behind the row of type-levers and in position to be struck by the face of the types when thrown backward (see Fig. 3) is placed the circular ink-pad receptacle U, suitably sustained by the corner and center posts u , and within this receptacle is held the ink-pad U', of felt or like material. The ink-pad receptacle is preferably formed in the shape shown, in order that both of the types of the type-carrying head may be properly inked.

The operation of this improved construction of type-lever and connected parts is as follows: Assume the type-carrying head of the lever to be provided with a "capital" and a "lower-case" type of the same letter, held, respectively, by the prongs 1 and 2. If the lower-case letter is to be printed, the corresponding finger-key of the key-board will be depressed, and the end of the catch-rod M^2 will raise the elbow-lever O, which in turn will throw the type-lever R downward toward the printing-point. As the type-lever has a pivotal center different from that of the turning-bar T, its downward movement causes the rack-bar t to rotate the pinion S' , and thereby to turn the type-carrying head S a sufficient distance to bring the lower-case type in position to print. As the main key-lever is retracted by the force of the spring m^2 , the type-lever is thrown again into a vertical position and the types are brought against the face of the ink-pad. If it is desired to print the capital letter on the prong 2 of the type-carrying head, the finger-key will be drawn backward at the same time that it is depressed, so as to cause the catch-rod M^2 to raise the arm of elbow-lever P, which movement as it is fully executed draws the post T' , turning-bar T, and rack-bar t by its connecting-link a sufficient distance to so far increase the revolution of the pinion S' as to bring the prong 2 with the capital letter to the common printing-center. As the lower-case types are those most frequently used, they are so placed upon the type-levers as to be struck by the simple vertical depression of the finger-keys. The keys are preferably cup-shaped, as shown, to enable them to be more readily drawn backward by the finger.

When a single type is to be carried by the type-lever, the pitman, the swinging plate, and other parts above described for shifting the position of the turning-lever will be dispensed with and the rear end of the main key-lever will be provided with a pin v , fitting within a hole in the bent end of the elbow-lever V, pivoted at v' to the main frame and connected at its upper end to the link V^2 , that is joined to the lower bent end of the single type-lever

W, pivoted at v^2 to the bracket-plate v^3 . Pivotedly connected to the upper end of the type-lever, as at v^4 , is the single-type-carrying head W', the bent end of which is pivoted to the upper end of the turning-lever X, as seen in Figs. 12 and 13. A pin x in the inner side of this turning-lever enters the curved slot x' of the type-lever. From this construction it will be seen that when the main key-lever is depressed the single-type-carrying lever W and turning-lever X will be forced downward, and the pin x of the turning-lever, riding in the slot x' , as shown in Fig. 4, will cause this lever to turn the type-carrying head into proper position for printing. As the key-lever is retracted by its spring, the type-lever will be thrown again into a vertical position and its type will strike the surface of the ink-pad.

20 Suitable blank keys will be employed to operate the escapement mechanism independently of the type-lever in order to form the necessary spaces between words.

From the foregoing description it will be seen that the operator has his work constantly before him where it can be seen at a glance and mistakes can be readily corrected. The construction of the type-carrying levers and turning-bars insures an effective inking of the types, and by the arrangement of several types upon a single lever the number and complexity of the finger-keys is much decreased.

It will be readily seen that the details of construction above set out may be varied within wide limits without departing from the scope of my improvements, and to such details, therefore, I do not wish the invention to be understood as restricted.

Having thus described my invention, what I claim as new, and desire to secure by Letters Patent, is—

1. In a type-writer, the combination of a series of pivotally-supported type-levers arranged to stand vertical in normal position, individual key-levers connected to the type-levers, a yielding and spring-actuated cross-bar beneath the key-levers, a driving-shaft D, carrying the escapement-wheel F, an escapement-pawl and stop-spring connecting the cross-bar and escapement-pawl, the flat paper-carriage having a rack-bar secured thereto, a

table to sustain the carriage, and a sliding pinion on the driving-shaft to engage the rack of the carriage, substantially as and for the purpose specified.

2. In a type-writer, the combination, with the paper-carriage, its rack-bar, and driving pinion and shaft, of an escapement-wheel and pawl, and a crank-arm for turning backward said shaft, and means, substantially as described, for connecting said crank-arm to said escapement-wheel, substantially as set forth.

3. In a type-writer, the combination, with the paper-carriage, its rack-bar, and driving pinion and shaft, of a perforated escapement-wheel loosely held on said shaft, a pawl or dog and spring for said wheel, and a crank-arm keyed to the driving-shaft and having a pivoted spring-seated arm and stop-pin, substantially as described.

4. In a type-writer, the combination, with a type-lever, of a type-carrying head pivotally connected thereto and provided with two separate types, a pinion and rack-bar for turning said type-carrying heads, and mechanism, substantially as described; for operating said type-lever and rack-bar, substantially as set forth.

5. In a type-writer, the combination, with the type-lever having the type-carrying head pivotally connected thereto and provided with two separate types, of a finger-key and mechanism, substantially as described, whereby the simple vertical depression of said key shall cause one of said types to act, and a vertical and horizontal depression of said key shall cause the other of said types to act, substantially as set forth.

6. In a type-writer, the combination, with a type-lever having a type-carrying head pivotally connected thereto, of a rack-bar and pinion, a main key-lever connected, substantially as described, with the type-lever, an elbow-lever connected with the end of the rack-bar, and means, substantially as described, for causing the main key-lever to actuate said elbow-lever, substantially as set forth.
